UNITED STATES PATENT OFFICE

JOHANNES KOSTEN AND FRANK ZUIDEMA, OF GRAND RAPIDS, MICHIGAN

DEVICE FOR PREVENTING FEATHER-PULLING IN FOWLS

Application filed March 23, 1931. Serial No. 524,508.

The main object of this invention is to provide a device for preventing feather pulling in fowls which is effective for the purpose and at the same time does not injure the fowl or prevent its feeding.

A further object is to provide a device of this character which is economical to produce and easily applied.

Objects pertaining to details and economies of our invention will appear from the description to follow. The invention is defined in the claims.

A structure embodying the features of our invention is clearly illustrated in the accompanying drawing, in which:

Fig. 1 is a conventional side elevation of the head of a fowl having our device applied to the upper mandible.

Fig. 2 is a cross section of the upper mandible on line 2-2 of Fig. 1, the mandible being shown conventionally and no attempt being made to indicate the internal form and structure thereof.

Fig. 3 is a cross section on line 3-3 of Fig. 2, the mandibles being shown conventionally.

Fig. 4 is a fragmentary plan view.

Fig. 5 is an interior perspective of a shield designed for the upper mandible.

Fig. 6 is an interior perspective of a shield designed for the lower mandible.

Fig. 7 is a perspective view of a modified form or embodiment of our invention.

In the accompanying drawing we represent the head of a fowl at 1 with upper mandible 2 and lower mandible 3. These parts are conventionally illustrated.

Our feather pulling prevention device comprises a sheath 4 formed of flexible resilient rubber and having inturned edge 5 adapted to engage the edges of the mandible to which the sheath is applied, the tip of the mandible projecting into a pocket-like portion 6 at the tip of the sheath.

The sheath is of such dimensions as to resiliently grasp or fit the mandible, and when designed for the upper mandible has inturned lug portions 7 engageable in the nasal fossa 8 so that the sheath has a very firm grip on the mandible and is not likely to become accidentally displaced. The sheath be-

ing of resilient material does not produce undesirable pressure on the beak and permits the growth of the fowl. The inturned edges of the sheath engage the other mandible at a point substantially spaced from the tip thereof as at 9 in Fig. 1, thereby preventing the complete closing of the mandibles and consequently preventing the grasping of a feather.

In Fig. 6 the sheath 10 has inturned edges 11 corresponding to the inturned edges 5 of the sheath 4 and has a central portion 12 which engages in the central recess in the lower mandible, thereby coacting with the inturned edges 11 and effectively retaining the sheath on the lower mandible. It is unnecessary, however, to employ a sheath for each mandible although the device may be adapted for either mandible and is effective in either case.

In Fig. 7, the sheath 13 has a complete inner wall 14, this particular sheath being adapted for the upper and/or lower mandible.

The habit of feather pulling is usually acquired when the fowls are quite young and in the rapidly growing stage. The device may be applied to such fowls without injury thereto. It permits considerable growth before renewal is necessary and it usually results that, the habit not having been formed, a larger sheath is unnecessary. The device does not seriously hamper the fowls in feeding.

Having thus described our invention what we claim as new and desire to secure by Letters Patent is:

1. A device for preventing feather-pulling in fowls consisting of a sheath of resilient rubber conformed to receive the upper mandible of a fowl and having inwardly turned edges embracing the edges thereof and inwardly projecting lug portions at its rear end engageable in the nasal fossa.

2. A device for the prevention of feather-pulling in fowls consisting of a sheath of resilient rubber-like material adapted to be disposed on a mandible of a fowl and having inturned edges with which the opposite mandible engages in spaced relation to its

tip, thereby preventing the closing of the mandibles at the tip, said sheath having a recess-engaging portion at its inner end.

3. A device for the prevention of feather-pulling in fowls consisting of a sheath of resilient rubber-like material adapted to be disposed on a mandible of a fowl and having inturned edges with which the opposite mandible engages in spaced relation to its tip, thereby preventing the closing of the mandibles at the tip.

4. A device for the prevention of feather-pulling in fowls consisting of a resilient rubber mandible sheath having inturned edges overlapping the edges of the mandible and resiliently grasping the mandible to which it is applied.

5. A device for preventing feather-pulling in fowls consisting of an elastic sheath of rubber-like material conformed to receive a mandible of a fowl and having inwardly curved edges embracing the edges thereof.

6. A device for preventing feather-pulling in fowls consisting of an elastic resilient sheath of rubber-like material conformed to receive a mandible of a fowl and having indented portions resiliently engaging recesses in the mandible.

7. A device of the class described consisting of a hollow conoidal substantially beak-shaped soft rubber sheath having an indented mouth-cavity portion.

8. A device of the class described consisting of a hollow conoidal substantially beak-shaped soft rubber sheath.

In witness whereof we have hereunto set our hands.

JOHANNES KOSTEN.
FRANK ZUIDEMA.
